REMOTE-CONTROL SWITCH STRUCTURE

Lathrop F. Berry and Flavius Eugene Davis, III,
Jackson, Mich.

Application August 4, 1947, Serial No. 765,914

2 Claims. (Cl. 200—87)

1

This invention relates to actuators, especially in conjunction with switches, and also in having to do with systems therefor with associations in multiple and even for primary and secondary operations.

This invention has utility when incorporated in solenoid or coil actuators for electric switches in diverse embodiments involving remote control, especially in the actuator circuit or circuits of the general character adequately cared for by annunciator wiring, as adapted to operate electric bells, and buzzers, instead of the usually much greater capacity of circuit carrying directly the voltage and amperage for lighting, normal household, office lighting and power circuits. With the signal or remote control circuit of say thirty volts or less, and the power requirement in the range of one hundred fifty watts, adequate safety wiring is had in the use of annunciator wire for the control circuit. The equipment as herein disclosed is adapted to be incorporated in a wide range of locations from ceiling or wall canopies, outlet boxes, junction boxes, and even from extensions. Single, multiple or even alternative control may be provided at adjacent or remote stations by the association therewith of actuators or actuators and diverse non-hazardous signal-like control circuits therefrom.

Referring to the drawings:

Fig. 1 is a vertical section thru a wall located outlet box having an embodiment of the switch actuator of the invention incorporated therein;

Fig. 2 is an enlarged view, from the front, of the oscillator feature of the actuator adapted for primary and secondary controls;

Fig. 3 is a plan view of some of the features of the oscillator of Fig. 2, and with a secondary control switch as operated thereby, in closed position;

Fig. 4 is a section on the line IV—IV, Fig. 3, but showing the switch of Fig. 3 in open position, and broken away in showing another, relatively angularly adjustable control with its switch in closed position;

Fig. 5 is a wiring diagram of an embodiment of the signal circuit wherein one actuator may have a position to nullify the other, which other has a plurality of stations;

Fig. 6 is a view of the oscillator of Fig. 2 in its normal position of rest, or as retracted and in position for a succeeding actuation; and

Fig. 7 is a wiring diagram involving a plurality of actuators disclosing the wide range for system assembly and interconnection in responding to manifold control requirements.

Electric power lines 1, 2 (Fig. 5), say for sixty 55

2

cycle and one hundred twenty volt supply electric current, may be in a usual household or office installation for concealed or conduit wiring in the range of desired uses, as illumination by a light 3.

Under the invention herein, say as from a bell, buzzer or other signal circuit, there is additional connections from a transformer 4 to step down the voltage. From such a signal circuit line 5, 10 a branch 6 is to one side of a coil 7. Another line 8 of the signal circuit from the transformer 4, has a branch 9 in which are located a plurality of switches 10. When adopting switches 10 of the push button type, they may be normally open and responding for circuit closing at the interval of depressing thereof. Upon closing any one of the switches 10, there is a connection to a line 11 extending from the other side of the coil 7, resulting in energizing of the coil 7. A core or plunger 12 (Figs. 1, 2) in the coil 7, normally 15 down in a brass guide tube 13 against a rubber or sound deadening cushion 14, is given a quick upward thrust from the current in the coil 7.

Pivoted upon and extending upward from the plunger 12 is a pointer or swing finger 15, adapted in the upward thrust of the plunger 12, to have its upper free end ride over a bracket wall 16 and somewhat back from an insulation disk 17 fixed on a shaft 18 extending thru the wall 16. Fixed 20 with the disk 17, on the side thereof toward the wall 16, is a segment or arc plate 19 having outwardly extending faces 20, 21, spaced by a less radial distance cam point 22 having therefrom diverging faces to the respective faces 20, 21.

From a fixed bracket 23, mounting the coil 7, there rises a lug 24, from which upwardly extends a tension helical spring 25 to a pin 26 thru the disk 17 into the plate 19 for rocking these parts together on the shaft 18 to one side or the other as above the medial or dead point of the shaft 18. The normal retracted position for the upper free end of the finger 15 is a centralized or neutral upward position, yieldably set by balanced tension spring 27 (Fig. 6). At stop positions, the point 22 of the cam is to one side or the other of the retracted finger tip 15. Energizing of the coil 7, causing outward thrust of the finger 15, has its tip ride along one side of the cam point 22 to push a face 20 or 21 in effecting a rocking of the shaft 18, clockwise or counterclockwise (Figs. 6, 20). The springs 25 direct the tip of the finger 15 to ride toward the shaft 18, while there is limit to outward throw or travel of the finger 15 by the pins 28, 29, from the wall 16. Upon de-en-

ergizing of the coil 7, the springs 27 retract the finger 15 to be clear of the point 22 and directed toward the shaft 18, in position for a succeeding thrust operation, regardless of the axial direction of the coil 7.

The shaft 18, in extending thru the bracket wall 16, may have fixed thereon a plurality of insulation disks or cylinders 30. The rocking of the shaft 18 thru an arc of about 90° for the face 20 away from the stop pin 28 limit position therefor, brings the face 21 to its stop pin 29. Fixed with the shaft 18, a thick insulation disk 30 has a pin 31 (Figs. 3, 4) or radial lug ride upward against a switch spring arm 32 to move its free end contact 33 against an opposing contact 34 on a yieldable arm 35 from a terminal 36.

The closing of the switch 33, 34, connects the electric power line 2 to a line 37 extending to the power consuming equipment to be controlled, herein shown as the light 3. This is an instance of the operation resulting from the closing of any one of the switches 10 in the momentary single thrust thereof. A succeeding operation of a switch 10 again thrusts the finger 15, but in its upward rise, instead of riding toward the face 20, it now rides toward the lower face 21 as directed by the cam 22, to have the face 21 move upward, as the face 20 comes down. Accordingly the shaft 18, and its carried parts, is oscillated in the reverse direction. This moves the pin 31 downward clear of the spring arm 32, so that it at once snaps clear of the contact 34, thus opening the circuit to the light 3.

The instance of the coil 7 and its repeating control of a power current switch is for the succeeding operation to be opposite or reverse. The signal circuit control may have the actuator including the coil 7 installed in a wall receptacle, junction box, or outlet box 38 (Fig. 1) which may have a closure front or plate 39 with one of the push buttons 10 thereon.

The range of adaptation is not necessarily to a switch outlet receptacle, but may be to other wall or ceiling receptacle, outlet box or canopy. For instance, in such latter receptacle, a coil 40 (Fig. 5) may have a circuit thereto by a line 41 from the signal circuit line 8. From the other line 5 of the signal circuit, by lines 6, 42, a push button switch 43, and a line 44, may complete a circuit to energize the coil 40 to throw its finger 15 to open and close a switch 45 to connect the power line 2 to a line 46 to the light 3. It is to be noted that with the switch 45 in the other side of the power supply to the light 3 than the switch 33, the switch 45 as open precludes any response for operation of the switch 33. Contrariwise, with the switch 33 open, the closing of the switch 45 does not turn on the light 3.

There is snap action in the rocking of the shaft 18 to operate the controls thereon. As the upwardly thrust finger 15 rides along a cam face 20 to rock such face away from its stop pin 28, the pin 26 puts the spring 25 under further tension in its lift to mid position above the shaft 18. Then as it rides past this center dead or mid position, there is a quick snap or rocking of the shaft 18 to have the face 21 strike its stop pin 29. The next or succeeding energizing of the coil 7 clears the face 21 from its pin 29 as the face 20 is brought to its stop 28. With a plurality of controls responding to the rocking of the shaft 18, one switch 33, 34, may be closed as another switch 47 (Fig. 4) is opened. Furthermore, an adjustable mounting 48 for lug 49 on this additional disk 30, makes available a special timing relation

therefor, which may be of value in determining a desired sequence in controls.

It may be considered that these operations due to the rocking of the shaft 18 are secondary, and that primary actuation may come from an arm 50 (Fig. 6) directly mounted on the finger 15 adapted to ride in the clearance between the pin 28 and the disk 17. In this transit, the arm 50 rigid with the finger 15, may operate a switch 51, say to connect a line 52 (Fig. 7) from the line 2, to a line 53 to a light bulb 54 having a line 55 therefrom to the line 1. This may be a flash illumination to serve as a signal that the actuator finger 15 really functioned.

Additionally, the finger 15 may carry other controls, as a pivoted arm 56 (Fig. 6) loaded to have its free end swing down in freely passing a switch 57 during the ascent of the finger 15, but as the finger 15 descends, a stop 58 holds the pivoted arm 56 to operate the switch 57 in a circuit having a line 59 (Fig. 7) thereto and a line 60 therefrom to a motor 61 having its circuit completed by a line 62 to a battery 63 as an independent energy source connected to the line 59.

The plural primary controls from the finger 15 may be for the other or reverse course with a switch 64 responding to the extended arm 50 for operating the switch 64 when the finger 15 be directed to have the arm 50 clear of the switch 51. The closing of the switch 64 may connect a line 65 with a line 66 to cut in a motor 67 having its circuit completed thru a line 68 to a battery 69.

The ascent rocking of the finger 15 as initially operating the switch 64 may in a slight almost instantaneous interval lag have the arm 56 extended to actuate a switch 70 connecting a line 71 from the line 8 with a line 72 to an audible signal or bell 73 with a line 74 therefrom to the line 5 of the signal circuit.

Besides the actuator coil 7, there may be additional sundry remote controls variously cut in or operated from similar actuator units at coils 75, 76, 77, 78. A single switch 10 is shown for the actuator coils 75, 76, which may therefrom have their fingers 15 oppositely actuated. Independent switches 10 may selectively control the actuators 77, 78, for thrusting the fingers 15 therefrom to rock shafts 18, or directly affect controls of the varied character of the switches 51, 57, 64, 70. In lieu of the two switches 10 for the coils 77, 78, there may be adopted a single switch 79 for cutting out a connection to one of the coils 77, 78 as the connection is cut in for the other coil 78, 77. It is to be noted that in the push button type of switch, the current consumption for the actuator is only instantaneous, for the duration of the switch depression. The various controls along the rock shaft 18 may retain the set or control position until there be a following actuation. There is thus provided duration for the secondary controls. With the switch 79 to determine a hold-in position, such duration may be of service in the primary controls from the finger 15.

What is claimed and it is desired to secure by Letters Patent is:

1. A compact switch-operating unit comprising a coil, a bracket wall having an opening in which opening the coil is mounted, said wall extending upwardly from the coil and there providing a bearing extending transversely of the wall, an insulation cam first disk mounted by the bearing, an additional switch operating second disk on the opposite side of the wall from and fixed with the cam first disk, a switch in prox-

imity to the second disk to be operated thereby, and a rockable finger carrying core adapted to be thrust by the energized coil to act on the cam disk for successively reverse rocking thereof.

2. In an electric control device, a bracket wall 5 having an opening therethru, an energizing coil in the opening, a core for and normally outwardly from the de-energized coil and at one side of the wall, a finger pivotally mounted on the core, yieldable directing means positioning 10 the finger normally to take the direction of core travel upon coil energizing actuation of the core, said bracket wall providing a bearing extending transversely of the direction of the core, a two-way throw cam rockably mounted at the bearing, 15 a disk spaced from the bracket wall by the cam in providing a guide way for finger thrust to rock the cam successively in opposite directions, a switch operating disk at the opposite side of the wall from the cam and coaxial of and fixed with 20 the cam, and a switch responsive to disk shifting to move to opposite control positions.
